UNITED STATES PATENT OFFICE.

HENRY E. DURKEE, OF GLASTONBURY, CONNECTICUT, ASSIGNOR TO PRATT & WHITNEY COMPANY, OF NEW YORK, N. Y., A CORPORATION OF NEW JERSEY.

DRESSING ATTACHMENT FOR GRINDING WHEELS.

Application filed February 20, 1922. Serial No. 538,018.

To all whom it may concern:

Be it known that I, HENRY E. DURKEE, a citizen of the United States, residing at Glastonbury, in the county of Hartford and 5 State of Connecticut, have invented certain new and useful Improvements in Dressing Attachments for Grinding Wheels, of which the following is a specification.

This invention relates to an improved 10 form of dressing attachment for grinding wheels and in particular to an attachment adapted to permit the accurate dressing or truing of a plurality of work engaging surfaces on a grinding wheel.

15 An object of the present invention is to provide a dressing attachment for grinding wheels especially adapted to dress or true a wheel for grinding screw threads. More particularly it is an object of the invention

20 to provide a dressing attachment which may be adjusted to properly true the work engaging surfaces of a grinding wheel so that the wheel will accurately grind the flanks and also the bottom surfaces of a screw

25 thread. This attachment is primarily intended for use with the thread grinding machine disclosed in my copending application Serial No. 538,017 filed February 20, 1922.

Another object of the invention is to form 30 the attachment in such a way that it will be readily adapted for adjustment for different types of threads and for the varying size of the wheel. Also that the dressing tool thereon may be easily operated manually and the 35 device may, when not in use, be pivotally swung about the grinding head so that it will be out of the way.

Another object of the invention is to provide guides or guiding members so arranged 40 on the attachment that the dressing tool may be accurately positioned while being passed across each of the work engaging surfaces of the wheel.

A still further object of the invention 45 that is of importance is that the guiding means for the dressing tool comprises pins outstanding from a flat surface on the attachment and arranged in pairs so that the dressing tool may be positioned against different pairs of pins for each surface of the wheel to be dressed.

Another feature which is advantageous 50 is that adjustments are permitted between different pairs of guiding members so that

the relative positions of the dressed surfaces 55 of the wheel may be varied. As the attachment is primarily adapted for screw thread grinding machines, one pair of guiding members is mounted directly on the grinding attachment and two other pairs of 60 guiding members are mounted on a plate, the position of which relative to the main portion of the attachment may be slightly varied. By this means the dressing tool may be so held that it will dress the work 65 engaging surfaces of the wheel in such a manner that the central portion of the wheel may have its width materially varied. By suitable adjustments of the plate relative to the body member of the attachment this central portion may be varied in width in accordance with the different forms and sizes 70 of screw threads being ground.

With these and other objects in view, my 75 invention consists in the features of construction and operation set forth in the following specification and illustrated in the accompanying drawing.

In the accompanying drawing annexed 80 hereto and forming a part of this specification, I have shown my invention embodied in a screw thread grinding machine but it will be understood that the invention can be otherwise embodied and that the drawing is not to be construed as defining or limiting 85 the scope of the invention, the claims appended to the specification being relied upon for that purpose.

In the drawing:

Figure 1 is a side elevation of a wheel 90 head provided with a dressing attachment made in accordance with the present invention.

Fig. 2 is a view of the dressing attachment looking in the direction of the arrow marked No. 2, shown in Fig. 1.

Fig. 3 is a front view of the dressing attachment looking in the direction of the arrow marked No. 3 in Fig. 1.

Fig. 4 is a transverse sectional view taken 100 on line 4-4 of Fig. 3.

Fig. 5 is a detached view of a form of dressing tool used in connection with this attachment.

Fig. 6 is an end view of the same.

In the above mentioned drawing, I have shown but one modification of the invention which is now deemed preferable but it is to 105

be understood that changes and modifications may be made within the scope of the appended claims without departing from the spirit of the invention.

5 Briefly, my invention in its broadest aspect comprises the following principal parts: namely, a frame adapted to be pivotally mounted upon the wheel head of a grinding machine; second, a body member adjustably 10 positioned thereupon; third, a plate movably mounted on said body member; fourth, positioning devices preferably in the form of pins on said plate adapted to retain a dressing tool in position while it is being 15 passed across the angularly disposed surfaces of the wheel; fifth, guiding means on the body member to position the dressing tool while operating upon a third surface of the wheel; sixth, means to adjust the plate 20 relative to the body member; and seventh, means to secure the attachment in operative position.

Referring more in detail to the figures of the drawing, I provide a wheel head 10 25 having an abrasive wheel 11 mounted upon a shaft 12 and rotating in suitable bearings provided within the wheel head 10. Preferably, the wheel 11 is provided with a protective enclosure 13 forming a part of the 30 wheel head 10. This protective covering 13 is provided with oppositely disposed projections or pads 15 on both sides forming the pivotal support for the frame 16 comprising the dressing attachment. These projections 35 or pads 15 are provided with pins 17 which are engaged by arms or extensions of the attachment member 16. From this construction, as shown in Figs. 1 and 3, it will be 40 seen that the dressing attachment 16 as a whole may be swung about an axis represented by the pins 17 on the wheel housing 13 and may thus be readily moved from operative to inoperative position. When it is not desired to use the attachment 16, it is 45 only necessary to elevate the forward portions thereof so that it may be swung about the pins 17 and rest upon the rear surfaces of the wheel head 10. When the attachment 50 is in operative position, a projection 18 provided on the attachment is in engagement with a stud 19 provided in the wheel head 10. A knurled nut 20 threaded to this stud 19 holds the attachment 16 firmly in operative position. For convenience, the pins 17 55 are provided with knurled nuts 17^a so that the member 16 may be securely clamped in operative position on the pins 17.

The attachment 16 may be made up of 60 separate members rigidly held together by means of screws 16^a.

On the forward portion of the attachment 16 a slide-way 25 is provided in which a body member 26 slides. To adjust the position of this body member 26 along the slide, 65 a screw 27 is provided having a nut 28 se-

cured in any preferred way to the attachment. The screw 27 is adapted to be rotated by means of a knurled handle 29. Mounted on the upper surface of this body member 26 on opposite sides are two pins 70 forming guides for a truing or dressing tool. One of these pins 31 is fastened directly to the upper surface of the member 26. The pin on the opposite side shown at 32 is positioned in a bracket member 33 secured to the 75 upper surface of the body member 26. These pins 31 and 32 are of identical diameters and are so positioned that their surfaces facing the abrasive wheel 11 are parallel to the axis of this wheel. The function 80 of these pins on body member 26 will presently be described.

The body member 26 is provided with a central depression in which a slide 35 may be adjustably positioned. Clamping screws 85 36 shown in Fig. 2 are provided permitting clamping of this plate 35 to the body member 26. The screws 36 pass through elongated slots 37 in the slide 35, thus permitting the slide 35 to be clamped in any desired 90 adjusted position. To vary the adjustment of this slide 35 relative to the body member 26 a screw 42 is provided extending through a projection mounted on the body member 95 26 and engaging one of the end surfaces of the plate 35.

On the upper surface of this plate 35 pins 38, 39, and 40, 41 are provided. These are so disposed relative to each other that when a dressing tool, to be presently described, is positioned against one or the other of these pairs of pins, it may be moved obliquely toward and from the wheel in a direction having a predetermined angular relationship to the axis of the wheel. If desired several plates such as that shown at 35 may be provided having guide pins positioned so that different angularly disposed surfaces may be formed on the wheel.

A suitable dressing or truing tool adapted 100 for use in connection with this attachment is shown in Figs. 5 and 6. This as will be seen comprises an elongated bar 50 having a small diamond holding member 51 outstanding from one of its sides. A screw 52 permits adjustment of this diamond holding tool to any desired position. Preferably, two pins 53 are provided in the upper surface of this bar 50 which may be grasped by the operator to aid in passing the tool across 115 the faces of the abrasive wheel.

Coming now to a description of the 120 method of operation of this device, the attachment is swung into its forward position as shown in Fig. 1 and secured in that position by means of the knurled nut 20. The body member 26 is then adjusted in position relative to the periphery of the wheel so that the dressing tool 50 may be positioned 125 in contact with the pins 31 and 32 and 130

passed across the outer periphery of the wheel. The position of the truing tool while engaged in dressing this surface of the wheel is shown in Fig. 2 in dotted lines. The dressing tool 50 may then be placed first in contact with one of the pairs of pins 38, 39 or 40, 41, and then in contact with the other pair. These pins are, as above described, fastened to and outstanding from the plate 35. With the truing tool in contact first with one of these pairs of pins and then in contact with the opposite pair, the truing tool is passed across the angularly disposed surfaces of the wheel.

It is obvious that with the plate 35 in one adjusted position relative to the body member 26, the surfaces on the wheel dressed by the attachment will form surfaces which are angularly opposed relative to each other in accordance with the positions of the pins 31, 32, 38, 39 and 40, 41. The pairs of pins 38, 39 and 40, 41 must be so positioned that they will give the required angular form to the lateral surfaces of the wheel and these two surfaces of the wheel must be positioned relative to the central peripheral surface of the wheel so that the correct width of the cylindrical portion will be formed. To vary the width of this central cylindrical portion of the wheel, it is necessary to vary the relative positions of the plate 35 and the body member 26. This is accomplished by means of screw 42.

It will be seen from the above description that a truing attachment has been provided which may be readily moved into and out of operative position and which may be used to dress a plurality of angularly disposed surfaces on a wheel. Also, that by means of a simple adjustment of a single screw 27, the attachment 16 may be so adjusted that it may be used for different sizes of wheels and may be adjusted to compensate for the wearing away of the wheel. Also that an independent adjustment by means of screw 42 has been provided which will permit relatively different positions between the cylindrical and conical surfaces dressed by the attachment so that it may be used to dress wheels for various sizes of screw threads having different widths of cylindrical surface at the bottom of the thread. Also, by substituting other plates 35 having the pins thereon differently arranged the wheel may be dressed with its side surfaces at any desired angles.

What I claim is:

1. A truing attachment for screw thread grinding machines comprising in combination, a body member adapted to be pivotally mounted whereby it may be swung into and out of operative position adjacent a grinding wheel, and guiding means for a dressing tool thereon whereby a dressing tool may be guided to true a plurality of surfaces of

said wheel, said guiding means comprising obliquely disposed pairs of pins outstanding from said body member.

2. A truing attachment for screw thread grinding machines comprising in combination, a body member adapted to be pivotally mounted whereby it may be swung into and out of operative position adjacent a grinding wheel, and guiding means for a dressing tool thereon whereby a dressing tool may be guided to true a plurality of angularly disposed surfaces of said wheel, said guiding means comprising pins arranged in pairs outstanding from said body member.

3. A truing attachment for screw thread grinding machines comprising in combination, a body member adapted to be pivotally mounted whereby it may be swung into and out of operative position adjacent a grinding wheel, and guiding means for a dressing tool thereon arranged in pairs whereby a dressing tool may be guided to true a plurality of surfaces of said wheel, said guiding means comprising pins outstanding from said body member, two of said pins being used to guide said dressing tool in each operative position.

4. A truing attachment for grinding wheels comprising in combination, a body member, a plate thereon, guiding means on said body member and plate for a dressing tool, a bar forming said dressing tool having a truing tool mounted therein adapted to be passed across a plurality of faces of said wheel while supported in position against said guiding means, and means to adjust the position of said plate relative to said body member whereby the relative positions of surfaces dressed by said tool may be varied.

5. A truing attachment for grinding wheels comprising in combination, a body member, a plate thereon, guiding means on said body member and plate for a dressing tool, a bar forming said dressing tool having a truing tool mounted therein adapted to be passed across a plurality of faces of said wheel while supported in position against said guiding means, means to adjust the position of said body member toward or from the wheel, and means to adjust the position of said plate relative to said body member whereby the relative positions of surfaces dressed by said tool may be varied.

6. A truing attachment for grinding wheels comprising in combination, a body member, a plate thereon, pairs of guiding means comprising pins on said body member and plate for a dressing tool, a bar forming said dressing tool having a truing tool mounted therein adapted to be passed across a plurality of faces of said wheel while supported in position against said guiding means, and means to adjust the position of said plate relative to said body member whereby the relative positions of surfaces dressed by said tool may be varied.

- 4
7. A truing attachment for screw thread grinding machines comprising in combination, a body member adapted to be positioned adjacent a grinding wheel, guiding means for a dressing tool on said body member a plate on said body member carrying pairs of guiding pins for dressing tools adapted to be passed across oppositely disposed surfaces of said wheel, means to adjust the position of said plate relative to said body member, and a dressing tool adapted to be positioned adjacent different pairs of guiding means.
8. A truing attachment for screw thread grinding machines comprising in combination, a body member adapted to be positioned adjacent a grinding wheel, a dressing tool therefor, guiding means for said dressing tool adapted to position it while being passed across the outer periphery of said wheel in a direction parallel to the axis of the wheel, a plate on said body member also carrying guiding means for said dressing tool and adapted to guide it while being passed across angularly disposed sides of
- 5 10 15 20 25
- said wheel, and means to adjust the position of said plate relative to said body member in a straight line whereby the relative positions of the surfaces dressed may be varied.
9. A truing attachment for screw thread grinding machines comprising in combination, a body member adapted to be positioned adjacent a grinding wheel, guiding means on said body member for said dressing tool adapted to guide said tool while being passed across the outer periphery of said wheel, a plate on said body member also carrying guiding means for said dressing tool, means to adjust the position of said plate relative to said body member in a direction toward or from the axis of rotation of said wheel whereby the relative positions of the surfaces dressed may be varied, and means to adjust the position of the body member toward or from the axis of rotation of said wheel.
- 30 35 40 45

In testimony whereof, I hereby affix my signature.

HENRY E. DURKEE.
